UNITED STATES PATENT OFFICE.

ABRAM S. KIRSHNER, OF PHILADELPHIA, PENNSYLVANIA, ASSIGNOR OF ONE-THIRD
TO SAMUEL M. KIRSHNER, OF PHILADELPHIA, PENNSYLVANIA.

PROCESS OF AND APPARATUS FOR EXTRACTING OIL.

Application filed November 6, 1920. Serial No. 422,282.

To all whom it may concern:

Be it known that I, ABRAM S. KIRSHNER, a citizen of the United States, and a resident of Philadelphia, in the county of Philadelphia and State of Pennsylvania, have invented certain new and useful Improvements in Processes of and Apparatus for Extracting Oil, of which the following is a specification.

10 This invention relates to a process of and apparatus for extracting liquid from any material such, for example, as cotton seed, and the object of the invention is a process of accomplishing this by acting upon the material by pressure, preferably hydraulic, and also subjecting the material to the action of centrifugal force so that the material is crushed and compacted by pressure and the liquid thrown therefrom centrifugally. The invention also relates to apparatus by which this process may be simply executed.

In the preferred embodiment, the material, such as cotton seed, is subjected to the quick and rapid blows successively delivered by hydraulic means while the material is also acted upon by centrifugal force created, for example, by the rapid rotation of the parts carrying the material being treated.

In the drawings accompanying and forming part hereof which show one form of apparatus for carrying out my process:

Figure 1 is a perspective view of a structure made in accordance with my invention.

Figure 2 is a vertical central section of the same.

Figure 2^a is a side elevation of a valve mechanism.

40 Figure 3 is a horizontal section through the line 3—3 of Figure 2.

Figure 4 is a sectional detail of several of the parts which, in the drawing, are shown before they are assembled in order that the construction of the parts may be better seen.

Figure 5 is a detail showing the same parts assembled.

Referring now to the details of the drawings by numerals: 1 designates an outside casing which may be of any desired form but is shown in the drawing as a casting having a support 2, the upper part being provided with two main chambers 4 and 5, one adapted to have the oil thrown into it and the other a chamber to receive the dried ma-

terial from which the liquid has been extracted, the chamber 4 having an outlet 7 through which the extracted liquid may pass, and the chamber 5 having a downwardly inclined chute 8 terminating in a spout 9 from which the dried material may pass from the machine. The upper part of the chamber 4 is provided with a head 12 having a hopper 14 by which the material to be treated is passed into the machine.

In the embodiment shown in my drawing, the main casting is also formed with an integral support as that shown at 15 for a bearing socket 16, the latter having bearings 18 and 20 for a tubular shaft 22, the latter being driven by any convenient means such as the belt 24 and pulley 26. The lower end of the tubular shaft 22 passes into a stuffing box 30 to which fluid power may be delivered by means of a pipe as 32 shown in Figure 2 which is connected to a valve as that shown at 33 in Figure 2^a, a supply pipe being shown at 33^a. Said valve is operated by a cam as 33^b so that at each rotation of the cam the machine is operated to allow the fluid pressure to charge and discharge from said pipe 32; thus the valve is designed to be opened and closed in rapid succession so that the fluid means will perform its work intermittently. The main casting 1 is further provided with a third or central chamber 36 to form a housing for the aforesaid tubular shaft 22, and also to afford a support for the bearings for the upper part of this shaft. To that end, the tubular shaft 22 passes entirely through the chamber 36 and is preferably screwed into one of the main members of my press designated by the numeral 40. This member 40 is directly under the hopper 14 and on its upper side is provided with a deep recess 42 to contain the plunger or piston 44, the latter also having a recess 46 in its upper surface to receive the material from the hopper. This member 40 is also provided with a downwardly projecting tubular central portion 48 which is screwed to the tubular shaft 22, as clearly seen in Figure 2, and is supported by bearings 50 and 52 so that the member 40 and its tubular portion 48 may be rotated with the tubular shaft 22. The upper end of the tubular shaft 22 opens into the said tubular portion 48, and the latter is open at its upper end so that the fluid medium may pass there-

from and into the deep recess 42 thereby forcing the plunger or piston 44 upward, the latter being provided with a packing ring 54 to make the same tight. The plunger 5 or piston 44 is provided with means, as the bolt 56 and spring 58, to permit the fluid pressure to force the plunger or piston 44 upward away from the member 40 of the tubular part, the spring 58 being arranged 10 to return the parts to the normal positions shown in Figure 2 as soon as the fluid pressure is released. Located over the member 40 is the second principal part of my apparatus which consists of an annular member 60, having a downwardly inclined portion 62, which member 60 is bolted to the member 40 so as to leave a chamber 63 between the two parts 40 and 62. The member 60 is provided with a projecting annular 20 bib 64, shown in Figure 2, and the plunger or piston 44 is intended to have its upper part projected into the space left by this bib so as to crush the material, as will be hereinafter explained. The inclined wall 62 is provided with a series of openings 68 and the inner surface of this wall is provided with the usual screening or haircloth covering 70. The parts 40 and 60 are bolted together by means of bolts 72 and nuts 74 so 30 that these parts are always maintained the proper distance apart and are compelled to rotate together. When the machine is first operated it is desirable to close the lower part of the chamber 63 between the parts 40 and 62 and for this purpose I provide a disk or plate 80 provided with an upward flange 82 which is designed to be moved up and down to open the close the bottom of the aforesaid aperture 63. This plate 80 and its 40 flange 82 are supported by a flange 86 formed on and projecting upwardly from a gear wheel 88. This gear wheel 88 is internally threaded to screw onto a screw threaded flange 90 projecting upwardly from the 45 housing of the bearings 50. If this gear wheel 88 is rotated in one direction, it will cause the disk or plate 80 and its flange 82 to ride upward to close the opening of the chamber 63 or, if rotated, in the opposite 50 direction, it will move said disk or plate 80 and its flange downward to open the mouth of said chamber 63. In order that the parts may be operated from the exterior of the machine I provide a shaft 92 having a 55 worm 94 (see Figure 3) which meshes with the aforesaid gear wheel 88, the said shaft 92 having a hand wheel 96 on the exterior of the machine by which said shaft may be rotated in one direction or the other.

60 The operation of my device is as follows: When the machine is first operated, the attendant rotates the hand wheel 96 to turn the worm 94 and rotate the gear 88 so as to elevate the disk or plate 80 and its flange 65 82 to close the mouth of the chamber 63.

Then the material to be acted upon is fed into the hopper 14. The material of course falls through said hopper into the recess in the piston or plunger 44 and as these parts are being rotated at a very high speed 70 by means of the belt 24 and the pulley 26, the said material is thrown outwardly by centrifugal force, passing over the flange of the piston or plunger 44. While said piston and its connected parts are being rotated at 75 high speed, the fluid pressure acts upon the under surface of said piston 44 and rapidly propels it upward into the space around the annular bib 64 crushing the material therebetween. As the valve is arranged to be 80 opened and closed with considerable rapidity, the said piston 44 is forced upward and then the spring 58 forces the piston back during which time the parts are rapidly rotating to affect the liquid centrifugally and 85 expel it through the openings 68. After the parts are thus simultaneously rotated and reciprocated until the operator finds that the chamber 63 is filled, he then rotates the hand wheel 96 to lower the flange 82 on the disk or plate 80 so as to open the mouth of the chamber 63. The operation of the machine will now cause the dry material to be ejected from the chamber 63 by centrifugal force 90 and into the chamber 5 from which it passes through the chute 9 into any suitable receptacle. During the time it takes for the material to pass from the deep recess in the piston or plunger 44 out through the chamber 63, during which time it will be understood that the piston is given rapid reciprocations against the member 60, there will be ample time for the liquid to be expelled centrifugally from the meal or other material 95 through the openings 68, before the dried cake reaches the mouth of the chamber 63 from which it is expelled.

100 It will be obvious that changes and modifications may be made in the form and construction of my apparatus without departing from the invention, and therefore reference should be made to the appended claims to determine the scope thereof.

110 What I claim as my invention is:

1. The method of extracting liquid which consists in subjecting the material to be acted on to the action of centrifugal force and at the same time to a succession of pressure blows.

115 2. In a structure of the character described, the combination of a pressure chamber, means for subjecting material to pressure intermittently, and means for acting on the material centrifugally.

120 3. In a structure of the character described, the combination of a pressure chamber, a piston or plunger therein for subjecting material to pressure intermittently, and means for rotating the parts at high speed 125 whereby the material is acted upon centrif-

ugally while it is being subjected to pressure.

4. In a structure of the character described, the combination of a pressure chamber, a piston or plunger therein, hydraulic means acting on said piston for compressing the material in said chamber, and means for rotating the parts at high speed whereby the material is acted upon centrifugally 10 while it is being subjected to pressure.

5. In a structure of the character described, the combination of a pressure chamber, a piston or plunger therein for subjecting the material to pressure, hydraulic 15 means for forcing said piston against the material, a spring for returning said piston to its normal position, and means for rotating the parts at high speed while the piston is being reciprocated.

20 6. In a structure of the character described, the combination of three main parts, two of them forming a chamber in which the material is subjected to action, a piston contained by one of said parts, hydraulic 25 means for forcing said piston against the other of said parts, and means for rotating all of said parts whereby the material is subjected to the action of centrifugal force during the operation of the piston.

30 7. In a structure of the character described, the combination of a casing, a tubular shaft journaled therein, two members rotatable with said shaft and having a chamber between them, a piston supported by one of said members and movable against the other member to compress the material therebetween, said tubular shaft arranged to deliver fluid pressure under said piston, and means for rotating said parts whereby the 40 material is subjected to centrifugal action while pressure is being exerted thereon.

45 8. In a structure of the character described, the combination of a casing having a hopper, a chamber into which liquid is expelled, and a chamber into which caked material is delivered, a tubular shaft suitably journaled in said casing, two members rotating with said shaft and having a chamber between them opening into the aforesaid chamber into which the caked material 50 is delivered, one of said members having

openings to deliver oil to the other chamber of the casing, a piston supported on one of said members and movable against the other, fluid pressure means acting through 55 said tubular shaft for forcing said piston against the opposite member, the tubular shaft and the parts connected therewith being rotatable at high speed whereby the liquid is ejected from the material by centrifugal force as the same is subjected to pressure.

9. In a structure of the character described, the combination of a chamber in which the material is subjected to action, 60 means for compressing the material, and means for regulating the size of the outlet of the chamber, said means comprising a disk, a gear connected with the disk and adapted to raise and lower the same, and 70 means for rotating the gear.

10. In a structure of the character described, the combination of a casing having a hopper, a chamber into which liquid is expelled, and a chamber into which caked material is delivered, a tubular shaft suitably journaled in said casing, two members rotating with said shaft and having a chamber between them opening into the aforesaid chamber into which the caked material 75 is delivered, one of said members having openings to deliver oil to the other chamber of the casing, a piston supported on one of said members and moving against the other, fluid pressure means acting through 80 said tubular shaft for forcing said piston against the opposite member, the tubular shaft and the parts connected therewith being rotatable at high speed whereby the liquid is ejected from the material by centrifugal force as the same is subjected to 85 pressure, a device for closing the outlet of the aforesaid chamber between the two main members, and means for opening and closing 90 said device.

In testimony whereof I affix my signature in presence of two witnesses.
